DESIGN FOR A TUMBLER

Willis O. Prouty, Hermosa Beach, Calif., assignor to Metlox Manufacturing Company, Manhattan Beach, Calif., a corporation of California

Application July 1, 1935, Serial No. 57,482

Term of patent 14 years

To all whom it may concern:

Be it known that I, Willis O. Prouty, a citizen of the United States and a resident of the city of Hermosa Beach, in the county of Los Angeles and State of California, have invented a new, original, and ornamental Design for a Tumbler, of which the following is a specification, reference being had to the accompanying drawings, forming part thereof, in which:

Figure 1 is an elevational view partly in section of the tumbler showing my design; and

Fig. 2 is a top plan view of the tumbler.

I claim:

The ornamental design for a tumbler substantially as shown and described.

WILLIS O. PROUTY.
